UNITED STATES PATENT OFFICE.

CARL L. NICKOLAI, OF DE BEQUE, COLORADO, ASSIGNOR OF FORTY ONE-HUNDREDTHS
TO EDWARD W. LLOYD, OF PUEBLO, COLORADO.

DOUBLE-UNDERREAMER SETTER.

1,157,577.

Specification of Letters Patent. Patented Oct. 19, 1915.

Application filed October 10, 1914. Serial No. 866,130.

To all whom it may concern:

Be it known that I, CARL L. NICKOLAI, citizen of the United States, residing at De Beque, in the county of Mesa and State of Colorado, have invented new and useful Improvements in Double-Underreamer Setters, of which the following is a specification.

My present invention pertains to means for setting under reamers; and it consists in the peculiar and advantageous appliance, hereinafter described and claimed, through the medium of which double under reamers of the oil-well type may be expeditiously and easily set by a single workman and without liability of injury to the workman.

In the drawings, accompanying and forming part of this specification: Figure 1 is an elevation illustrating the application of my novel appliance to a double reamer. Fig. 2 is a perspective of the appliance *per se*. Fig. 3 is a detail section illustrative of the manner in which the adjusting nut is secured in the body of the appliance.

Similar numerals of reference designate corresponding parts in all of the views of the drawings.

The under reamer illustrated is of conventional construction, and among other elements comprises a body 1 and a key-carrying mandrel 1^a in which is a central threaded socket designed to receive the adjusting stem 2 of my appliance.

In addition to the stem 2 the setting appliance comprises a frame 3 and an adjusting nut 4. The appliance frame 3 is formed of a single piece of metal suitable to the purpose, and has a base bar 5 and arms 6 that reach at right angles from the base bar and are provided in their upper ends with notches 7. For the sake of increasing the stiffness and strength of the frame without rendering the same unduly heavy, both the base bar 5 and arms 6 are ribbed as indicated, by 8. The base bar 5 is provided with a central smooth-bore aperture 9 for the loose passage of the stem 2 and is also provided with a depending collar 10 on the wall of which is an inwardly-extending projection 11, preferably a screw as shown. The

stem 2 is slightly tapered as shown, and is provided with an upper thread 12, a lower thread 13, and a head or finger-piece 14, the latter at its lower end. The adjusting nut 4 is rotatable in the collar 10 of the frame 3, is threaded to engage the lower thread of the stem 2, and is provided with a circumferential groove 15, the latter to receive the projection 11 which serves to swivel the nut in the collar 10. On the nut 4 is a handle 16.

In the practical use of the appliance, the frame 3 is set up against the base of the under reamer, Fig. 1, so that the notches in the arms of the appliance frame receive the fins 17 on the body 1, and the stem 2 is turned into the threaded socket in the lower end of the key-carrying mandrel 1^a. With this done, the nut 4 is turned through the medium of the handle 16, whereupon the mandrel 1^a will be drawn downwardly sufficiently far to permit of the key, the cutters 70 and the setting ring of the under reamer being adjusted.

It will be gathered from the foregoing that a single workman can quickly apply my appliance to and manipulate it on an under reamer, and that incidental to the use of the appliance there is no liability of anything slipping and injuring the hands of the workman.

Having described my invention, what I claim and desire to secure by Letters-Patent, is:

An appliance for the purpose described, comprising a U-shaped frame having notches in the ends of its arms, a stem having a threaded upper end and also having a threaded portion extending through the base bar of the frame, and a nut swiveled in the base bar of the frame and receiving and engaging the last-named threaded portion of the stem.

In testimony whereof I have hereunto set my hand in presence of two subscribing witnesses.

CARL L. NICKOLAI.
